United States Patent

Des. 241,833

Patented Oct. 12, 1976

241,833

BUILDING STRUCTURE

Bernhoff A. Dahl, P.O. Box 164, Hampden
Highlands, Maine 04445

Filed Jan. 20, 1975, Ser. No. 542,598

Term of patent 14 years

Int. Cl. D25—03

U.S. Cl. D25—13

FIG. I

FIG. 2

FIG. 3

FIG. 4

FIG. 1 is a plan view of such structure looking downwardly onto the roof thereof;

FIG. 2 is a perspective view of the structure in FIG. 1 looking from one corner thereof as shown by arrow A;

FIG. 3 is a perspective view of the structure in FIG. 1 looking from a second corner thereof as shown by arrow B; and

FIG. 4 is a perspective view of the structure in FIG. 1 looking from a third corner thereof as shown by arrow C.

I claim:

The ornamental design for a building structure, substantially as shown.
